DESIGN FOR A BEVERAGE COOLER

Sydney A. Conway, Bloomfield, N. J.

Application March 29, 1944, Serial No. 113,059

Term of patent 14 years

(Cl. D67—2)

To all whom it may concern:

Be it known that I, Sydney A. Conway, a citizen of the United States and a resident of Bloomfield, in the county of Essex and State of New Jersey, have invented a new, original, and ornamental Design for a Beverage Cooler, of which the following is a specification, reference being had to the accompanying drawing, forming part thereof.

Figure 2 is an end elevational view of the article, the dotted lines representing a fragmentary portion of the walls of the refrigerator casing being shown for illustrative purposes only.

I claim:

The ornamental design for a beverage cooler, as shown and described.

SYDNEY A. CONWAY.
